WIRE SPLICER

George T. Stafford, Houston, Tex.

Application July 3, 1942, Serial No. 449,585

6 Claims. (Cl. 140—123)

The invention relates to a wire splicer of the type wherein a metallic or other sleeve of suitable material is deformed about the adjacent ends of the wire which is being spliced.

In connection with overhead wires it is necessary that the wire splice is sufficiently strong to support the weight of the wire and the tension thereon without being deformed and to transmit a load or stress at least equal to that which can be sustained by the wire itself.

Various type wire splicers have been devised heretofore but most of them are cumbersome and incapable of adjustment so as to compensate for alignment or wear.

It is one of the objects of the present invention to provide a wire splicer wherein the dies for deforming the connection are capable of movement to effect alignment thereof and to be adjustable so as to compensate for wear.

Another object of the invention is to provide a wire splicer wherein the supporting structure for one of the dies is capable of adjustment so as to compensate for wear on the dies and other parts of the splicer.

Still another object of the invention is to provide a wire splicer wherein a block and slot arrangement is provided so that the block may be adjusted to position the die in different relative positions.

Still another object of the invention is to provide a wire splicer wherein a tremendous pressure may be applied by disposing the parts to obtain a maximum mechanical advantage.

Another and further object of the invention will be readily apparent when the following description is considered in connection with the accompanying drawings wherein:

Figure 1 is a side elevation of the wire splicer with the dies in closed position.

Figure 2 is a top plan view of the splicer of Figure 1.

Figures 3 and 4 are sectional views taken on the lines 3—3 and 4—4, respectively, of Figure 1.

Figure 5 is a side elevation of the splicer in open position for adjusting or arranging the dies.

Figure 6 is a sectional view of the wire which is being spliced.

The splicing machine is intended for use for the purpose of splicing the wire as in Figure 6 wherein the wire 2 is being spliced to the wire 3, and these two wire ends are installed in a metallic or other suitable sleeve 4 so that the ends thereof are closely adjacent to each other and extend a substantial distance into the sleeve. The sleeve is then to be crimped and deformed as

shown by the depression 5, and is forced into close contact with the wire portions 2 and 3. As seen in Figure 6, the first depressions are made nearly in the center of the sleeve 4 and are alternated on opposite sides away from the center so that the material making up the sleeve 4 is gradually deformed and elongated by the pressure applied to it by the dies 6 and 7, which form the parts of the splicer.

10 The splicer is shown in open position in Figure 5 and constitutes a frame 10 having the foot pieces 11 by which it will be supported upon a surface. This frame has a standard or upright 12 thereon which is rigidly anchored to the frame. This standard is arranged to removably support the die 6 which is of a suitable form to engage the wire or retainer sleeve of the splice being made. This die 6 has a shank 14 thereon which is slidable in a groove in the standard 12. A lug 15 affixed to the standard retains the die against upward movement. The upper end of the standard is constructed with a forked end 16 so as to provide the space 17 between the forks. A groove 18 extends downward into the fork portions of the arm from the rear side thereof and is adapted to receive the cross pin 19 carried by the lever linkage mechanism 20. This construction forms an anchor for the leverage mechanism as will be hereinafter described.

15 20 The frame 10 also carries the leverage linkage mechanism 20 which has the links 21 pivoted at 21 to the member 22. The handle 20' is pivoted at 21" to the other end of the links 21" so that the three pivots 23, 21 and 21" allow movement of the leverage from the position of Fig. 5 to that of Fig. 1. This member is in turn pivoted at 23 to the frame. The pivot 23 is spaced somewhat from the standard 12 as seen in Figure 5.

25 30 The member 22 has a vertical slot 23' therein which is arranged to receive the shank 24 of the die 7. This construction is best seen in Figures 1 and 3.

It will be noted as seen in Figure 1, that the shank 24 is capable of considerable movement in slot 23' but is restrained to some extent by a block 25 which is mounted on a pin 26. This pin 26 passes through the spaced legs 27 of the member 22. In order to allow for a loose or adjustable movement of the die 7 relative to the member 22 the shank 24 is provided with an opening or slot 29 which receives the block 25. As best seen in Figure 1, the opening 30 in the block 25 which receives the pin 26, is off center so that the distance from the opening to the

edges of the block in each of the four directions therefrom is different. The block being substantially square can be changed in position in the slot 29 so that in substance the die 7 and its shank 24 can be adjusted relative to the member 22 by merely changing the position of the block by turning a quarter, one-half or three-fourths turn, as may be desired depending upon the adjustment of the die. It seems obvious that this adjustment will not only compensate for wear on the parts but will compensate for different sized sleeve 4 and for other variations in size of the material and equipment. A cap screw 31 may be used to retain the shaft or pin 26 in place.

The eccentricity or off center position of the opening 30 relative to the block or edges of the block, permits four adjustments of the block and consequently four adjustments of the die 7 relative to the member 22. These adjustments as indicated above compensate for variations in wear and alignment and in the size of the materials and equipment.

In actual operation the splicer will be open, as seen in Figure 5, the wire ends 2 and 3 arranged in the sleeve 4 and the sleeve position in front of the die 6. The member 22 and the leverage mechanism 20 is then raised so as to position the cross pin 19 in the slot 18 in the upper end of the standard 12. The leverage member is then swung around in a counter-clockwise direction so that the cross pin 19 is firmly seated in the slot 18. This movement brings the dies 6 and 7 together as seen in Figure 1, and further movement of the leverage mechanism creates a tremendous pressure due to the position of the fulcrum 19 and the great mechanical advantage thus obtained by this leverage. Every time the splicer is closed, an indentation such as 5 is made. It seems obvious that the alternate indentation can be quickly made so as to deform the retainer sleeve 4 and to firmly clamp it upon the wire ends.

While the invention has been described in detail as applied to the crimping of the retainer sleeve in the splicing of wire, it seems obvious that by changing the dies the device could be used as a punch or a shear as desired.

Broadly, the invention contemplates a splicer wherein the dies will be loosely mounted to compensate for alignment and wherein one of the dies is adjustable to compensate for wear and difference in size of the materials.

What is claimed is:

1. A wire splicer comprising a frame, a standard extending upwardly therefrom, a die removably held by said standard, an anchor portion on said standard, a member pivoted on said frame to move to a position substantially parallel to said standard, a die on said member to cooperate with said first die to crimp the wire being spliced, and a lever linkage mechanism having a means to releasably engage said anchor portion as a fulcrum to exert a high pressure on said dies.

2. A wire splicer comprising a frame, a standard extending upwardly therefrom, a die removably held by said standard, an anchor portion on said standard, a member pivoted on said frame to move to a position substantially parallel to said standard, a die on said member to cooperate with said first die to crimp the wire being spliced, a lever linkage mechanism having a means to releasably engage said anchor portion as a fulcrum to exert a high pressure on said dies, and means to adjust one of said dies to compensate for wear and alignment.

3. A wire splicer including a pair of relatively movable members, a die on each member, means including a pivoted linkage to force the members and dies together by a coupling of the linkage to effect the splicing, means to loosely support one of said dies for alignment, including an adjustment for the die to vary its position relative to the member supporting it so as to compensate for wear, said adjustment comprising a block and slot arrangement with a pin to support said block and an opening in the block which is off center so as to provide a plurality of different adjustments by disposing said block in different angular positions in the slot.

4. A support construction for the die of a wire splicer comprising a member, a recess therein, a die, a shank on the die to slide in the recess, a slot in the shank, a block in said slot, an off center opening in the block, a pin in the member extending across the recess and through the block so that disposing of the block in different positions in the slot accomplishes different adjustments of the block and die relative to the member.

5. A wire splicer of the type for crimping a sleeve about two wire ends including a frame, a die carried thereby, a member pivoted on said frame, a die adjustably carried by said member so as to vary its position relative to said first die, and a leverage linkage pivoted to the other end of said member and including a pair of spaced links, a handle pivoted thereto, and a cross pin on said handle, means on said frame to receive said cross pin whereby movement of said handle actuates said linkage to obtain the mechanical advantage thereof in applying pressure to said dies so as to deform the sleeve about the wire ends.

6. A device of the character described for crimping, punching or shearing comprising a body, a die fixed thereon, a member pivoted to said body, a die thereon to be moved to cooperate with said first die when said member is pivoted, and a handle linkage connected to the free end of said member and including an eccentrically mounted portion to engage said body so as to provide a mechanical advantage in forcing said dies together.

GEORGE T. STAFFORD.
